UMBRELLA FOR USE ON BOATS

Jesse M. Garrett, Longview, Tex.

Application June 15, 1949, Serial No. 99,327

1 Claim. (Cl. 248—38)

1

The present invention relates to sturdy and relatively large umbrellas sufficient in size to shield a plurality of persons, and has more particular reference to a novel clamp and staff construction for such an umbrella which will allow the umbrella to be conveniently erected on fishing skiffs and boats and employed for protection against sun and rain but used, primarily, as a "sail" for propelling said boat.

It is now common knowledge that umbrellas in the category under consideration have been used in the above capacities and that it is popular practice on fishing crafts used on lakes to rely on an umbrella as a "sail" while trolling. The difficulty has been that unless a wide range of adjustments be available, the umbrella, when open, of course, cannot be satisfactorily employed to gain best propulsion results. Confronted with this problem, I have now worked out a simple, practical and efficient structure which has to do primarily with the staff construction and find that my special adaptations make it feasible, indeed, to employ an umbrella, customarily used for protection against rain and sun, as an effective sail.

Briefly, novelty is predicated upon an umbrella of suitable size and strength for intended purposes and a strong sectional staff, said staff being made up of several units combining their functions and utilities in providing a series of individual and collective adjustments susceptible of attaining the wanted ends with requisite nicety and reliability.

One phase of novelty has to do with a staff construction having a clamp at one end, an umbrella at the opposite end, and a plurality of interconnected and intervening complementary units or sections, the latter being arranged to provide at least two joints with the parts working on horizontal axes, and a joint between the staff and clamp which swivels on a vertical axis, whereby the parts, all working together, permits the umbrella to be tilted at an advantageous angle in respect to the wind and swivelled about, as the wind changes, the results being attainable conveniently by the duly appointed occupant of the boat.

Other objects and advantages will become more readily apparent from the following description and the accompanying illustrative drawings.

In the accompanying sheet of drawings, wherein like numerals are employed to designate like parts throughout the views:

Figure 1 is a view primarily in elevation but partly in section, showing an umbrella and complements constructed in accordance with the in-

2

vention and showing the clamp attached to a seat on a boat or the like (not shown);

Figure 2 is also an elevational view with the structure removed from the boat seat and observing same by looking at Figure 1 in a direction from right to left;

Fig. 3 is an enlarged fragmentary sectional and elevational view on the line 3—3 of Figure 1, looking in the direction of the arrows; and

10 Figure 4 is a similar enlarged fragmentary sectional and elevational view on the line 4—4 of Figure 2, looking in the direction of the arrows.

It may be pointed out, by way of introduction to the detailed description, that the clamping means, the unit which I identify generally by the numeral 7, may be attached as shown to a boat seat board 8 or may be, of course, attached to the side or gunwale of the boat.

Referring now to the drawings by distinguishing reference numerals, we will start with the stated clamp 7 which comprises upper and lower jaws 9 and 10 and a body portion 11, which body portion is shown provided with a tapered bore or passage 12 into which the screw-threaded 20 shank of a set screw 13 projects. The lower jaw 10 is also provided with a set screw 14, here shown engaged with the bottom of the seat board 8.

The first unit of what may be referred to as a triple section staff for the umbrella 15 is shown 30 mounted wholly on the clamp. This unit or section, identified at 16, comprises a stub member 17 having a reduced tapered spindle portion 18 which is swivelly mounted in the correspondingly tapered bore 12. The lower protruding end of 35 the spindle is threaded to accommodate a knurled finger-adjusted clamping nut 19. With the nut 19 and set screw 13, it is possible to quickly and effectively adjust the unit 16 in relation to the clamping unit 7. Unit 16 also includes a circular centrally apertured head member 20 having a toothed surface. This headed member is opposed to a complementary headed disk or member 21 which is also toothed and the coacting teeth of the respective heads are denoted generally at 40 22. These members 20 and 21 provide an adjustable positive clamp type joint which constitutes what may be called the lower joint 23. A tapered bolt 24 with a knurled grip 25 serves to effectively bind and clamp the heads 20 and 21 together to perfect a reliable joint. The head 21 is carried by a vertically disposable tube 26 constituting the intermediate section of the umbrella staff. The upper end of tube 26 is longitudinally slotted, tapered and screw-threaded 45 to provide gripping jaws 27 and these are sur-

50 55 to provide gripping jaws 27 and these are sur-

rounded by a screw-threaded collet 28 which is suitably knurled and provided with a set screw 29 to engage the jaws 27. The features 27 and 28 provide a clamping collet for the lower telescoping and adjustable end portion of the tubular member 30. This adaptation wherein 30 is suitably "chucked" in the tube 26 allows for lengthening the overall dimension of the staff. The upper end of tube 30 is welded at 31 (see Fig. 3) to a disk-like jointing head 32 forming a complementary part of the upper joint 33. The remaining part of the joint is a complementary head 34 with the faces of the heads 32 and 34 having gear teeth 35 securely joining the heads together. A bolt 36 is threaded into the central screw-threaded hole in the head 32 and said bolt has a tapered or conical shank 37 which is wedged into a conical bore in the head 34. The screw or bolt, as it may be called, is provided with a knurled adjusting grip 38. The uppermost staff section 39 is welded at 40 to the head 34 and is connected at its upper end in any suitable manner with the collapsible umbrella 15.

I know of no sturdily built umbrella for both protection against sun and rain which may be adequately used as a fishing boat "sail" while trolling on lakes and the like which has a staff and clamp arrangement constructed as herein shown and described. Novelty is predicated upon the clamp unit 7 to which the lower unit or section 16 of the staff is swivelly connected. Novelty is also predicated upon the clamp 7 with a swivelly mounted unit 16 forming an essential part of a hinge joint 23 which connects the intermediate section 26 of an umbrella shaft to a clamp. Thus, the clamp is detachable, unit 16 may be swivelled, and the hinge joint 23 may be adjusted to angle the section 26 in relation to the clamp or boat as the case may be. Novelty is predicated upon the second or upper clamp 33 which is telescopically connected by way of the tubular member 30 with the intermediate staff section 26 and which clamp forms an essential part of the uppermost staff member 39 which carries the umbrella proper. So, we have a staff which is primarily made up of sections 26 and 39 connected by a hinge joint wherein the two sections are regulatable on a horizontal axis, permitting the section 26 to be angled at a 45° pitch in relation to the boat and the other section to be angled in a somewhat opposite direction to cant or tilt the umbrella over the boat. With the two sections thus in somewhat V-shaped relationship, the entire umbrella and shaft may be swivelled on the vertical axis provided between the spindle 18 turning in the bore 12 of the clamp 7. The tapered bolts which assemble the heads of the respective joints 23 and 33 serve to securely bind the respective clamping heads together and make the adjustment of parts easy on the fingers.

Although the invention has been described primarily for use on fishing boats, it is obvious that it may be used in other fields of endeavor. That is to say, it may well be used as protection against rain, snow, sleet and wind on tractors, plows, automobiles, chairs, benches, tables, wagons, bathing beaches and so on, thus to serve

the needs of welders, drivers, drilling attendants, bathers, and so on and so forth.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claim.

Having described the invention, what is claimed as new is:

A convertible boat type umbrella support comprising a clamp for attachment to a fixed support, said clamp having a tapered open-ended vertical bore, an adapter unit embodying a vertical stub member having a shoulder and a reduced tapered spindle below said shoulder, said spindle being swivelled in said bore and having a screw-threaded lower end portion passing through and beyond said bore and provided with a thumb nut adapted to clamp either loosely or tightly against said clamp, a set-screw carried by said clamp and releasably engageable with said spindle, said shoulder resting rotatably on said clamp, a jointing and hinging head carried by the upper end of said stub member, an elongated staff section provided on its lower end with a complementary jointing and hinging head opposed to said first-named head, an assembling and binding bolt piercing said heads and providing a combination clamp and hinging joint, a third hinging and jointing head detachably, rotatably and extensibly mounted on the upper end of said staff section, a second staff section adapted to carry an umbrella canopy on its upper end, a fourth hinging and jointing head mounted on the lower end of said second staff section and opposed to said third-named head, and an assembling, clamping and hinging bolt passing through said third and fourth-named heads, said bolts being parallel to each other and at right angles to said spindle and the detachable, rotatable and extensible mounting between the third head and first staff section embodying a chuck carried by the upper end of said latter section.
